UNITED STATES PATENT OFFICE.

CHARLES E. NUTTING, OF HOPEDALE, MASSACHUSETTS, ASSIGNOR TO DRAPER CORPORATION, OF HOPEDALE, MASSACHUSETTS, A CORPORATION OF MAINE.

BOBBIN-CLUTCHING MEANS FOR ROTATABLLE SPINDLES.

1,265,947.

Specification of Letters Patent. Patented May 14, 1918.

Application filed October 31, 1917. Serial No. 199,469.

To all whom it may concern:

Be it known that I, CHARLES E. NUTTING, a citizen of the United States, residing at Hopedale, county of Worcester, State of 5 Massachusetts, have invented an Improvement in Bobbin-Clutching Means for Rotatable Spindles, of which the following description, in connection with the accompanying drawing, is a specification, like characters on the drawing representing like parts.

This invention relates to bobbin driving means for rotatable spindles for spinning, twisting and similar apparatus of that type wherein a rotatable bobbin rest and spindle 10 is provided with a plurality of concentrically arranged centrifugally-acting bobbin-clutching means for holding the yarn carrier or bobbin securely in place upon the spindle.

It is desirable in this type of spindle to 15 provide means located between the spindle and the bobbin-clutching members which shall be yieldingly actuated vertically to effect in coöperation with the said members the equal and symmetrical expansion or 20 outward movement thereof and also to provide radially interengageable means on said spindle and on said bobbin-clutching members near the upper ends of the bobbin-clutching members for the purpose of re-

stricting the radial outward movement of 25 the upper end of the bobbin-clutching members when the spindle is running bare. The means employed for thus yieldingly radially expanding the bobbin-clutching members is 30 usually a vertically actuated device such as an upwardly spring pressed cam shaped ring engaging cam surfaces on the interior of the bobbin-clutching members and there is therefore always a positive tendency to raise the 35 bobbin-clutching members vertically. The effect of this action is to bring the bobbin-clutching members into vertical engagement 40 with the means on the spindle for limiting the radial movement of the upper ends of the bobbin-clutching members. The result 45 is that a wearing action takes place which frequently so wears away or destroys the interengageable parts of the bobbin-clutching members and the means on the spindle to 50 limit radial movement that the bobbin-clutching members work loose at their lower ends in, and fall out from, the bobbin rest.

The object of this invention is to provide, in combination with the vertically acting 55 and yieldingly actuated expanding means,

means carried by the bobbin rest and engaging the lower ends of the bobbin-clutching members and acting thereby to prevent the bobbin-clutching members from having the undesirable vertical movement and thus 60 preventing vertical engagement of the radially interengageable means employed to limit radial movement of the bobbin-clutching members while at the same time permitting the required radial movement of the 65 bobbin-clutching members.

More specifically the invention provides a construction in which the bobbin rest is provided with a vertical annular recess, in which the bobbin-clutching members are provided 70 with radially projecting feet having an annular groove on the upper surface thereof, and in which an expandible ring is inserted in the recess in the bobbin rest and held in engagement therewith over the groove in the 75 feet so as to prevent the vertical movement of the bobbin-clutching members while permitting the required radial movement thereof.

These and other features of the invention 80 will more fully appear from the accompanying description and drawings and will be particularly pointed out in the appended claims.

The drawings show so much of a rotatable 85 spindle as is necessary to a disclosure of the present invention.

In the drawings,

Figure 1 is a side elevation of a rotatable 90 spindle provided with a preferred embodiment of the present invention, some of the parts being broken away to show a portion of the construction and the lower end of a bobbin being shown in vertical cross section mounted thereon;

Fig. 2 is a view similar to Fig. 1 with a portion of the construction shown in vertical cross section and with the bobbin removed showing the parts in the position assumed when the spindle is running bare;

Fig. 3 is a view in horizontal cross section taken on the line $x-x$ of Fig. 1;

Fig. 4 is a view in vertical cross section of a detail of the construction shown in Fig. 2 with the parts much enlarged.

The general construction is of a familiar type including the vertical spindle 1 projecting upwardly from, and concentrically secured in, the bobbin rest 2. The usual whirl 3 affords the means from which the 110

entire device is given the necessary rotation.

The lower end of a bobbin 4 of usual type is shown in cross section in Fig. 1. This 5 bobbin is provided with a vertical bore fitting over the spindle 1 and at its lower end this bore is enlarged at 5 to fit over and engage the bobbin clutching means by which the bobbin is held fast to, and concentrically 10 with, the spindle thus securing its rotation with the spindle.

A plurality of bobbin-clutching members 6, herein shown as three in number, are mounted upon the spindle and bobbin rest 15 and rotate bodily therewith. The exterior surface of these bobbin-clutching members is generally cylindrical and conforms to the inner surface of the portion 5 of the bore of the bobbin, the extreme upper ends 7 of the 20 bobbin-clutching members being curved inwardly to permit the bobbin readily to be slid thereover.

In the construction illustrated as embodying the preferred form of this invention 25 these bobbin-clutching members at their lower ends are provided with radially projecting flanges or feet 8. The inner lower edge is chamfered off at 9 more readily to permit the desired rocking movement of the 30 clutching members. On the upper surface of the feet 8 an annular groove 10 is provided.

The bobbin rest 2 is provided with a vertical recess 11 therein extending concentric 35 with the spindle 1 and down below the surface 12 upon which the butt of the bobbin is seated when in place. On the interior vertical wall 13 of this recess an annular groove 14 is formed. The bobbin-clutching 40 members are assembled with their lower ends located in the recess 11 and then an expandable split ring 15 is forced downwardly until it snaps into the groove 14 and fits over the groove 10 in the upper surface of the 45 feet 8.

The bobbin-clutching members are given a positive radial expanding movement by a means located between the spindle and the said members which is yieldingly actuated 50 vertically to effect in coöperation with the said members the required expansion thereof. For this purpose the bobbin-clutching members are shown as provided upon their interior surfaces with an annular cam surface 55 16 and a sleeve 17 is mounted to slide vertically on the spindle 1 and has a complementary cam surface 18 coöperating with the cam surface 16. This sleeve 17 is yieldingly pressed vertically upward by a helical 60 spring 19 surrounding the spindle 1 and located between the sleeve 17 and an integral annular sleeve-like portion 20 of the bobbin rest 2.

It will thus be seen that the action of the 65 yieldingly and vertically upwardly projected

sleeve 17 in coöperation with the bobbin-clutching members is to give a symmetrical radial outward movement of the bobbin-clutching members.

This radial movement of the bobbin-clutching members is limited by radially interengageable means on the spindle and on the said members near the upper ends of the latter. These means are shown as a collar 21 secured to the spindle and provided with 70 a downwardly projecting annular flange 22 coöperating with a complementary vertically upwardly projecting annular flange 23 on the interior of the bobbin-clutching members. The interengagement radially of the 75 flanges 22 and 23 limits the radial movement of the bobbin-clutching members.

The action of the means employed for expanding the bobbin-clutching members, if not prevented, is such that it necessarily 80 has a strong tendency to elevate bodily the bobbin-clutching members and bring about a vertical engagement of the bobbin-clutching members and the flange of the collar 21. The result is that so much wear takes place 85 between the collar 21 and the bobbin-clutching members by reason of this vertical engagement that the flange 22 is worn off or cut into or the flange portion of the bobbin-clutching members is worn off or cut into or 90 both sufficiently to permit the lower ends of the bobbin-clutching members to come out of the recess in the bobbin rest thus permitting the bobbin-clutching members to fall out of place. This action is, however, 95 prevented by this invention in the construction already described because any vertical movement of the bobbin-clutching members is prevented by the ring 15.

The construction, however, permits the 100 necessary radial movement of the bobbin-clutching members because they may pivot freely about the ring 15.

The bobbin-clutching members are held in proper spaced relation about the spindle 110 by suitable separator pins 24 vertically mounted in the bobbin rest.

The construction thus provided is simple, efficient and readily manufactured and assembled, the radially projecting grooved 115 feet of the bobbin-clutching members are readily made by machine operations and the parts are readily assembled by simply snapping the ring 15 into place. In addition if it is desired to remove any of the bobbin-clutching members for repair or replacement the ring 15 may be sprung out of its seat in the recess 11 thus permitting the bobbin-clutching members to be removed.

Having fully described my invention, 125 what I claim as new and desire to secure by Letters Patent is:

1. The combination of a rotatable bobbin spindle and bobbin rest, a plurality of centrifugally-acting, bobbin-clutching members 130

mounted upon and bodily rotatable therewith, radially interengageable means on said spindle and on said members to restrict the radial movement of said members, vertically 5 acting means to effect in coöperation with said members the expansion thereof, and means carried by the bobbin rest engaging the lower ends of said members and acting to prevent said members from moving vertically 10 and thereby prevent vertical engagement of said radially interengageable means and acting to permit the required radial movement of said members.

2. The combination of a rotatable bobbin 15 spindle and bobbin rest, the said bobbin rest having a vertical recess therein concentric with said spindle, a plurality of centrifugally-acting bobbin-clutching members mounted upon and bodily rotatable there- 20 with and provided with radially projecting feet at their lower ends located in said recess, radially interengageable means on said spindle and on said members near the upper ends thereof to restrict the radial movement 25 of said upper ends, means located between said spindle and said members and yieldingly actuated vertically to effect in co-operation with said members the expansion thereof, and an expandible ring engaging the 30 outer vertical wall of said recess and overlying said feet and acting to prevent said members from moving vertically thus to prevent vertical engagement of said radially interengageable means and acting to permit 35 the required radial movement of said members.

3. The combination of elements as set forth in claim 2 in which in addition the feet of said bobbin-clutching members are provided with an annular groove on the upper 40 surface thereof fitting beneath said ring.

4. The combination of a rotatable bobbin spindle and bobbin rest having a vertical recess therein concentric with said spindle, a plurality of centrifugally-acting bobbin-clutching members mounted upon and bodily rotatable there- 45 with and provided with radially projecting feet at their lower ends located in said recess, and an expandible ring engaging the outer vertical wall of said re- 50 cess and overlying said feet.

5. The combination of elements as set forth in claim 4 in which the feet of the said bobbin-clutching members are provided with an annular groove on the upper surface 55 thereof fitting beneath said ring.

6. The combination of elements as set forth in claim 4 in which the outer vertical wall of said recess is provided with an annular groove in which the said ring is seated.

7. The combination of elements as set forth in claim 4 in which the feet of said clutching members are provided with an annular groove on the upper surface thereof 65 fitting beneath said ring and in which the outer vertical wall of said recess is provided with an annular groove in which the said ring is seated.

In testimony whereof, I have signed my 70 name to this specification.

CHARLES E. NUTTING.
